UNITED STATES PATENT OFFICE.

CHARLES FRANKLIN JONES, OF NEW YORK, N. Y.

COUPON-SAFE.

No. 923,532.

Specification of Letters Patent.

Patented June 1, 1909.

Application filed June 30, 1908. Serial No. 441,073.

To all whom it may concern:

Be it known that I, CHARLES FRANKLIN JONES, a citizen of the United States, and a resident of the city of New York, borough of Manhattan, in the county and State of New York, have invented a new and Improved Coupon-Safe, of which the following is a full, clear, and exact description.

My invention relates to safes, my more particular purpose being to provide a safe containing a supply of coupons connected together in the form of a strip, and further containing means controllable by the entrance of coins for feeding out the coupons.

It will be understood that the coupons above mentioned may serve as receipts for money, and that instead of coupons the strips of transient material may contain tickets, stamps or other loose pieces of paper or cardboard, such as are usually issued in pieces of definite length.

Reference is to be had to the accompanying drawings forming a part of this specification, in which similar characters of reference indicate corresponding parts in all the figures.

Figure 1 is a perspective showing the coupon safe complete; Fig. 2 is a longitudinal section through the safe, showing the coin wheel receiving a coin and ready to be turned in order to discharge the coin into the safe, thereby causing a coupon to be fed out; Fig. 3 is a vertical section taken upon the line 3—3 of Fig. 2, and showing the coin-controlled mechanism including a coin wheel, and a spring pawl normally holding the wheel and liberated for a moment by the insertion of a coin, this view further showing a knob for turning the coin wheel by hand and showing also the roller mechanism for feeding the strip representing the coupons; and Fig. 4 is a detail of the spring pawl for locking the coin wheel, this spring pawl being provided with a wide portion to be engaged by the coin as the latter passes under it, in order to disengage the spring pawl from the coin wheel.

The safe is shown at 5, and is provided with a door 6 and a lock 7 for securing the door. Mounted within the safe is a wall 8 having a portion 9 bent abruptly, as indicated in Fig. 3 and secured to the interior of the safe. The portion 9 bends upwardly at 10, as will be understood from Fig. 2, thus having an arcuate form. Another wall 11 is disposed inside of the safe and is bent

obliquely upward, as will be understood from Fig. 2.

Disposed opposite the wall 8 (see Fig. 3) is a smaller wall 12. The walls 8, 12 serve mainly for supporting certain movable parts 60 hereinafter described. A coin wheel 13 is keyed upon a revoluble stub shaft 14, the latter being provided with a knob 15, thereby adapting it to be turned by hand. The safe is provided with a coin slot 16, and disposed immediately adjacent to the latter is a spring pawl 17, this spring pawl being provided with a wide portion 18 and with a downwardly projecting tooth 19.

The spring pawl is secured against the top 70 portion of the safe by aid of bolts 20, and has a general arcuate form as will be understood from Figs. 2 and 4. The coin wheel 13 is provided with a number of shallow slots 21, spaced equidistant and each being of arcuate 75 form. A coin is shown at 22, and is adapted to fit into any one of the coin slots 23, of which four are provided in the coin wheel 13. The coin when inserted into the slots projects from the coin wheel a distance representing 80 approximately one-half the diameter of the coin.

A gear wheel 24 is secured rigidly upon the stub shaft 14 and is parallel with the coin wheel 13. This gear wheel meshes with a 85 pinion 25, and this pinion is connected rigidly with a roller 26, the pinion and roller being supported by the walls 8 and 12. The roller 26 is provided with bosses 27. Immediately above the roller 26 is a roller 28; provided 90 about its middle with an annular channel 29, which is in registry with the bosses 27. A revoluble shaft 30 serves as a reel, and wound upon it is a roll 31 of paper which is in the form of a ribbon 32. This ribbon extends 95 through a guide 33 and is fed out into lengths representing coupons 34. Each length, when torn off, becomes a coupon and may conveniently serve as a receipt for the coin deposited.

The operation of my device is as follows: The parts being in their respective normal positions, a coin 22 is dropped through the slot 16. This coin just misses the spring pawl 17, and drops into the particular coin 105 slot 23 which happens to be immediately adjacent to the coin slot 16. The operator now grasps the handle 15 and turns the same in a contraclockwise direction, as indicated by the arrow in Fig. 1. The coin wheel thus turns, 110

with the result that the coin 22 now engages the under side of the wide portion 18 of the spring pawl. This lifts the spring pawl so as to disengage the tooth 19 from the coin wheel 13; that is to say, the tooth 19 is simply raised out of the particular slot 21 which it happens to occupy at the moment.

The coin wheel 13 being turned still further, the coin clears the wide portion 18 of the 10 spring pawl, and the tooth 19 enters the next successive shallow slot 21, thereby locking the coin wheel in position. The further rotation of the coin wheel now discharges the 15 coin into the safe, as indicated by dotted lines in Fig. 2. The machine is now ready to receive another coin through the slot 16. Each time a coin is deposited as above described, the coin wheel is turned exactly one-fourth of a revolution. Each time the coin 20 wheel thus turns, the gear wheel 24, being like the coin wheel 13, rigid upon the stub shaft 14, turns the pinion 25 and consequently the roller 26.

The ribbon 32, being engaged by the bosses 25 27 and also by the roller 28, is drawn from the roller 31 and fed through the guide 33 a distance sufficient to leave a portion 34 extending, this portion being, in effect, a coupon. The operator tears off this portion and 30 keeps it as a receipt for the coin deposited.

I do not limit myself to any particular type of safe or other receptacle to be used in connection with my coin-controlled apparatus; neither do I restrict myself to the par-

ticular construction of coin-controlled mech- 35 anism shown, except in so far as the same is limited by my claim which defines the scope of my invention.

Having thus described my invention, I claim as new and desire to secure by Letters 40 Patent:

The combination of a receptacle provided with a coin slot, a coin wheel mounted within said receptacle and provided with coin slots for receiving coins from said coin slot, and 45 further provided with slots disposed intermediate said coin slots in a plane different from that of said coin slots, and a spring pawl made of a single piece of spring metal and connected with said receptacle and provided 50 with a portion normally extending into some one of said last-mentioned slots for the purpose of preventing undue rotation of said coin wheel, said spring pawl being further provided with a portion extending into the 55 path of a coin carried by said coin wheel so as to lift said spring pawl when said coin wheel is turned in one direction, said coin being free to fall, from its own gravity, after its release from said spring pawl.

In testimony whereof I have signed my name to this specification in the presence of 60 two subscribing witnesses.

CHARLES FRANKLIN JONES.
